UNITED STATES PATENT OFFICE.

EDWARD H. KIMBALL, OF GLENCOE, ILLINOIS.

CUTTING-MACHINE.

SPECIFICATION forming part of Letters Patent No. 693,404, dated February 18, 1902.

Application filed December 31, 1900. Serial No. 41,697. (No model.)

To all whom it may concern:

Be it known that I, EDWARD H. KIMBALL, a citizen of the United States, residing at Glen-coe, in the county of Cook and State of Illinois, have invented certain new and useful Improvements in Cutting-Machines, of which the following is a specification.

My invention relates more particularly to improvements in machines used for cutting paper in which a vertically or diagonally reciprocating knife is suspended in a frame; and the object of my invention is to provide such a cutting-machine which shall be simple, compact, and strong.

By my invention I am enabled to provide in small compass an inexpensive and yet powerful machine which may be readily operated, easily kept in order, and quickly and cheaply repaired.

A machine embodying my invention can be constructed so as to be readily portable and, occupying small space, may be attached to a counter or similar convenient place in a store and so provide a practical and efficient machine for cutting or trimming the pages of periodicals and the like, either in quantities or from time to time as the same are sold over the counter. These and such other objects as may hereinafter appear are attained by the device illustrated in the accompanying drawings, in which—

Figure 1 represents a side elevation, partly in section, of an apparatus embodying my invention in its preferred form. Fig. 2 represents a vertical section on the line 2 2 of Fig. 1 looking in the direction indicated by the arrows. Fig. 3 represents a horizontal section on the line 3 3 of Fig. 1, and Fig. 4 represents a horizontal section on the line 4 4 of Fig. 1.

Similar letters of reference indicate the same parts in the several figures of the drawings.

Referring by letter to the accompanying drawings, A represents a base of any suitable form, preferably provided with the channel a for the cutting-block X.

B is the frame of the cutter, of any suitable form and dimensions, but shown in the drawings as cast with a U-shaped cross-section.

The frame B is adjustably mounted upon the lugs C, which are cast upon the base A, by means of the slots c and the headed studs b,

which pass through the slots c and are screwed into the sides of the frame.

D is a knife suspended from the frame B by the toggles E F and G H, each of said toggles consisting of two links which are pivoted together at their adjacent ends, the upper ends of the links E G of the toggles being pivotally secured within the frame B and the knife being separably pivoted to the lower ends of the toggle-links F H. The toggles E F and G H are connected together by the link I, and the link I and toggle G H are pivotally connected, by means of the link J, with the short arm k of the lever K, which lever is pivotally secured to one of the uprights of the frame B. The knife is also pivotally secured to the frame by the additional link L.

It will be noted that the sides of the flanges of the frame B near their lower ends are thickened, so as to narrow the space between them to approximately the thickness of the knife. The purpose of this, as clearly shown in Figs. 2 and 4, is to provide guides at each end of the frame for the knife D.

The operation of my device is as follows: The lever K being swung forward to the position shown in dotted lines in Fig. 1 tends to force the link J backward in a horizontal plane. This in turn, by reason of the pivotal attachment of the link J to the knuckle-pivot of the toggle G H and the pivotal connection by means of the link I between the knuckles of the toggles G H and E F, tends to force the knuckles of the toggles backward and upward in the arc of a circle, thereby lessening the distance between the points of attachment of the toggles to the frame and to the knife, respectively, and resulting in the elevation of the knife. If, however, the cutter were constructed without the supplemental link L, pivotally attached to the knife and to the frame, the action of the toggles would result simply in the vertical lifting of the knife.

As it is desired, however, to obtain a shearing action by the knife, I provide this supplemental link L, whereby when the movement of the toggles tends to lift the knife vertically the link L is swung thereby backward and upward in the arc of a circle, forcing the knife to travel in substantially a diagonal path upward and backward. In this movement and the reverse movement the lo-

cation of the link L is advantageous, this for the reason that weight of the knife is borne by the toggles and not by the link, the latter serving merely to regulate the direction of movement of the knife. There is therefore no requirement of a heavy casting, such as is required where the knife is supported by a link, serving to cause a shearing movement. Furthermore, there is but a single link required, thus insuring that the knife will move with a shear cut and yet retain a true horizontal position during such movement, the toggles necessarily moving in unison. The knife having been so elevated, the parts will all be brought to the positions shown in dotted lines in Fig. 1. Thereupon the periodicals or other matter which it is designed to cut having been suitably secured in position upon the cutting-box X, preferably by a supplemental press, which may be attached to the back of my cutter, but which is not shown in the drawings, the lever K is swung backward and downward, thereby allowing the operator to apply his weight and strength to the best advantage, the link J is pulled forward by the short arm k of the lever K, and by means of the pivotal connections above noted tends to forcibly pull the knuckles of the toggles E F and G H into a straightened position, thereby forcing the knife downward against the matter to be cut. At the same time the link L causes the knife-blade in its downward travel to swing forward, the combined action of the toggles and the link L resulting in a simultaneously forward and downward movement of the knife, whereby a shearing cut is produced.

It will be obvious that by my combination of the lever K with the toggles and the link L, I have produced within small compass and of simple construction a powerful paper cutter or trimmer, which can be practically operated by hand-power.

While I consider the construction shown, in which I suspend the knife from a pair of toggles, to be the preferable and most effective means of embodying my invention, it is apparent that the knife is capable of being suspended by a single toggle, the use of a pair of toggles only serving to steady the knife and to distribute the strains incident to the operation of my device. It is also apparent that with a longer or heavier knife the knife may be suspended from as many toggles as may be deemed expedient under the particular circumstances of each case.

While I have shown the frame adjustably attached to the base, so that the frame may be lowered from time to time to compensate for the wear of the knife because of repeated sharpenings, it is obvious that such adjustable feature is not essential to the spirit of my invention, and even when it is desired it may be provided in other well-known ways—such, for instance, as by means of slots in the knife where it is attached to the toggles.

It is also obvious that various modifications in the form and dimensions of the various parts may be made without departing from the spirit of my invention.

Having thus described my invention, what I claim, and desire to secure by Letters Patent, is—

1. In a cutting-machine, the combination of a base, a frame mounted thereon, a knife suspended from said frame by a pair of toggles, a link connecting the knuckles of said pair of toggles, an operating-lever pivoted to said frame and adapted to articulate said toggles, and means for moving said knife in a direction to give a shear cut, substantially as described.

2. In a cutting-machine, the combination of a base, a frame mounted thereon, a knife suspended from said frame by a toggle-joint, a link pivotally attached to said frame and also pivotally attached to said knife, and means mounted upon said frame for articulating said toggle, whereby said knife will have a movement to give a shear cut, substantially as described.

3. In a cutting-machine, the combination of a base, a frame mounted thereon, a knife suspended from said frame by a pair of toggles, a link connecting the knuckles of said pair of toggles, a supplemental link pivotally attached to said frame and also pivotally attached to said knife, and an operating-lever pivoted to said frame and adapted to articulate said toggles, whereby said knife will have a movement to give a shear cut, substantially as described.

4. In a cutting-machine, the combination of a base, a frame mounted thereon, a knife suspended from said frame by a pair of toggles, a link connecting the knuckles of said pair of toggles, a supplemental link pivotally attached to said frame and also pivotally attached to said knife, an operating-lever pivoted to said frame and connected by a link with the knuckle of one of said toggles, whereby said knife will have a movement to give a shear cut, substantially as described.

5. In a cutting-machine, the combination of a base, a frame adjustably mounted thereon, a pair of toggles pivoted at their upper ends to said frame, a knife pivotally attached to the lower ends of said toggles, a link connecting the elbows of said pair of toggles, an operating-lever adapted to articulate said toggles, and a supplemental link having pivotal connection with said frame and with said knife, whereby said knife will have a movement to give a shear cut, substantially as described.

6. In a cutting-machine, the combination of a base, a frame mounted thereon, a knife suspended from said frame by a plurality of toggles, an operative connection between the elbows of said toggles, means mounted upon said frame for articulating said toggles, means for moving said knife in a direction to give a

shear cut, and vertical guides for said knife formed within said frame, substantially as described.

7. In a cutting-machine, the combination of a base, a cutting-block carried thereby, a frame mounted thereon, a knife suspended from said frame by a plurality of toggles, an operative connection between the elbows of said toggles, means mounted upon said frame for articulating said toggles, means for moving said knife in a direction to give a shear cut, and vertical guides for said knife within said frame, substantially as described.

8. In a cutting-machine, the combination with a frame; a knife suspended from said frame by a pair of toggles; and an operating-lever and connections for articulating said toggles, whereby said knife will be given a vertical movement; of means connected to

10 said frame and to a single point on said knife 20 for controlling the path of movement of the knife.

9. In a cutting-machine, the combination with a frame; a knife suspended from said frame by a pair of toggles; and an operating-lever and connections for articulating said toggles; of a link pivoted to said frame in juxtaposition to the pivot-point of said lever and having its opposite end pivotally connected to the knife coincident with the pivot-point of the near member of the toggle, whereby said knife will be given a shear movement under the action of the lever.

EDWARD H. KIMBALL.
